BALLASTING SYSTEM FOR LOCOMOTIVES

Carleton K. Steins, Overbrook, Pa., assignor to
The Pennsylvania Railroad Company, Phila-
delphia, Pa., a corporation of Pennsylvania

Application November 29, 1949, Serial No. 130,035

6 Claims. (Cl. 105—75)

1

This invention relates to ballasting systems for locomotives, particularly for locomotives wherein the body contains a fuel storage compartment in one end and a fuel consuming power source such as a steam boiler in the other end, and wherein the body is supported at its opposite ends by separately-powered swivelled trucks with spring suspensions respectively beneath the fuel compartment and the boiler. The ballast system of my present invention is in effect an improvement upon a generally similar one disclosed in a co-pending application Serial No. 656,912 filed by me on March 25, 1946, now Patent No. 2,590,473 in which water is used as the ballast medium and automatically transferred from a water storage compartment in a coupled tender to a ballast compartment in the fuel compartment on the locomotive as the fuel is consumed, and vice versa, when the fuel is replenished, so that the load maintained on the truck beneath the fuel compartment is always equal to that on the truck beneath the boiler and slippage is thereby prevented between the drivers of the two trucks.

The chief aim of the instant invention is to provide, in a ballasting system of the kind referred to, a flow control means which is more sensitive, as the fuel supply decreases or is replenished, and which will accordingly respond more quickly to relaxation or flexure of the springs of the truck supporting the fuel and water ballast compartment end of the locomotive than the corresponding means of my prior application supra.

Other objects and attendant advantages will appear from the following detailed description of the attached drawings, wherein—

Fig. 1 is a view, in side elevation, of a steam locomotive conveniently embodying my present invention.

Fig. 2 is a transverse section through the body of the locomotive taken as indicated by the angled arrows II—II in Fig. 1.

Fig. 3 is a fragmentary view, in side elevation, of a portion of the front end of the locomotive drawn to a larger scale and showing pump and valve means through the media of which the transfer of the ballast water is induced and controlled.

Fig. 4 is a view corresponding to Fig. 3, drawn to a still larger scale and showing certain of the parts in section.

Fig. 5 is a fragmentary view in transverse section taken as indicated by the angled arrows V—V in Figs. 3 and 4.

Figs. 6 and 7 are fragmentary views correspond-

2

ing to Fig. 4 showing the control valve in different positions of operation.

The locomotive herein illustrated and generally designated by the numeral 20 in Fig. 1, is identical with the one shown in my aforementioned prior application, and to it is connected a tender 21 by means of the coupling at 22. Within the rear end of the locomotive body 23 is an horizontally-elongate boiler 24 which provides the steam for operating the engines (not illustrated) of independently swiveled powered front and rear trucks 25 and 26 respectively having multiple driving wheels 27 and 28. After common practice in the art, the trucks 25 and 26 are provided with spring suspensions as conventionally indicated, and associated with them respectively, are smaller wheeled independently swiveled leading or guide trucks 29 and 30. Within the front end of the locomotive body 23 are a compartment or bunker 31 for fuel, and two flanking compartments 32 (Fig. 2) for ballast water, these several compartments being disposed directly over the front truck 25, while the weight of the boiler 24 is supported directly above the rear truck 26. Within the tender 21 is a ballast water reserve or storage compartment 33, and extending between the latter and the water ballast compartment 32 on the locomotive is a pipe line 40, 41. Interposed in the piping 40, 41 is a rotary pump 42 and a reversing slide valve 43 which are supported from the body of the locomotive at the level of the main frame 44 of the front truck 25 over the associated guide truck 29 as best shown in Fig. 3. The pump 42 is direct connected to a driving turbine 45 supplied with steam from the boiler through a pipe 46, the flow being regulatable by means of the hand valve at 47. The end ports 50 and 51 of control valve 43, see Fig. 4, are in communication with the suction and pressure sides of the pump 42 by way of pipes 52 and 53; and between said ports is a by-pass 54 which connects with the section 40 of the water transfer line through a short branch 55. The check valve at 56 prevents reverse flow in the pipe 53. Opposite the by-pass 54, the body of control valve 43 has another by-pass 57 which is connected to the section 41 of the line conduit by a short branch 58. The slide 61 of the valve 43 has spaced circumferential grooves 62 and 63, and normally occupies the neutral position in which it is shown in Fig. 4, so that water will be normally circulated tidily through the pump 42 by way of the pipes 52 and 53 and the then communicating ports 50, 51 and 54 in the valve body as

indicated by the arrows in Fig. 4, the by-pass 57 being closed at this time.

The improved automatic control means, with which the present invention is more especially concerned, includes a horizontally-arranged cylinder 65 which is hung from the body of the locomotive, and whereof the piston rod 66 is directly connected to the piston 61 of control valve 43. A spring 67 acts upon the piston 68 in the cylinder 65 to maintain the valve 43 normally in the neutral position in which it is shown in Fig. 4. Extending from the front end of cylinder 65 is a pipe 69 which, through a flexible tube 70, is connected with the upper end of a second cylinder 71 which is vertically disposed and secured to the frame 72 of the small leading or guide truck 29 associated with the front drive wheel truck 25. The lower end of the piston rod 73 of cylinder 71 is diametrically reduced, as shown at 73a in Fig. 4, and passes loosely through an aperture in a shelf bracket 75 projecting outwardly from the equalizer bar 76 of the guide truck 29 at the center as shown in Fig. 5. At its protruding end, the piston rod 73 is provided with a stop nut 77. Seated on the shelf bracket 75, with its upper end engaged by a cap collar 78 fast on the piston rod 73, is helical compression spring 79.

Liquid, such as oil is used in the cylinders 65 and 71, the oil being supplied from a reservoir 80 on the locomotive body, through a pipe 81 which extends downward to a T fitting 82 at the juncture between the pipe 69 and the flexible tube 70. By means of the stop valve indicated at 83, a definite constant amount of the oil is trapped in the cylinders 65 and 71 and in the piping 69, 70.

Operation

As previously stated, the valve 43 is normally in neutral position so that water is idly circulated through the pump 42 as indicated by the arrows in Fig. 4. As fuel is consumed and the load on the front drive truck 25 tends to lighten, with attendant relaxation of the main springs of said truck as well as the springs of the associated leading guide truck 29, upward movement of the cylinder 71 will take place relative to its piston. As a consequence of the suction thus created in the top of cylinder 71, liquid is drawn from the cylinder 65, whereupon the piston 68 of the latter is forced by the spring 67 to draw the slide 61 of valve 43 to the right as in Fig. 6. As a consequence water will be transferred, by action of the pump 42 and by way of the piping 40 and 41, from the reservoir 35 in the tender 21 to the ballast compartments 32 on the locomotive to compensate for the fuel weight loss. This action will of course take place occasionally during travel of the locomotive, the frequency depending upon the speed at which the locomotive is driven and hence the rate of fuel consumption, and will not be influenced by spasmodic action of the truck suspension springs in view of the flexible connection of the piston rod 73 of cylinder 71 with the equalizer bar 76 of the guide truck 29 through the spring 79.

Upon subsequent refilling of the fuel compartment 31 and consequent increase of the load on the front truck 23 and flexing of its suspension springs, liquid will be forced from the cylinder 71 into the cylinder 65, and act upon the piston 68 of the latter to compress the spring 67 to force the slide 61 of valve 43 leftward as in Fig. 7. Under these conditions, water will be transferred by the pump 42 through the piping 40, 41, from

the ballast compartments 32 on the locomotive to the storage compartment 35 on the tender to compensate for the increased weight of the replenishing fuel on the front drive truck 25. In this way, it will be seen that the load on the front truck 25 is automatically maintained uniform and equal, at all times, to the constant boiler weight on the rear truck 26 of the locomotive, to the advantage of effectively preventing slip as between the drivers of the two trucks.

Having thus described my invention, I claim:

1. A ballasting system for a locomotive having a body with a fuel storage compartment in one end thereof, and a fuel consuming power source of constant weight at the other end thereof, separately-powered drive wheel trucks with spring suspensions yieldingly supporting the body respectively beneath the fuel compartment and beneath the power source, and a coupled tender; said system including a ballast water compartment in the fuel compartment end of the locomotive body, a water storage compartment in the tender, piping between the ballast water compartment and the water storage compartment in the tender, a continuously operating pump interposed with a flow control valve in the piping, a cylinder with a piston for actuating the valve and with spring means influential upon the piston to maintain the valve normally set for idle circulation water in the pump, a vertically-arranged cylinder mounted upon a spring cushioned member of the truck beneath the fuel compartment end of the locomotive with its piston rod connected to a spring-supporting member of said truck, and a flexible conduit serially connecting the two cylinders whereby, upon relaxation of the springs of said truck as fuel is consumed, fluid is displaced from the last mentioned cylinder into the first mentioned cylinder to move the piston of the latter and thereby actuate the valve for transfer, by the pump, of fuel weight loss compensating water from the tender to the water ballast compartment and maintenance of a constant load on the powered truck beneath the fuel compartment end of the locomotive body.

2. A ballasting system for a locomotive according to claim 1, wherein the connection between the piston rod of the second mentioned cylinder is flexible to the extent of permitting normal up and down movement of the truck without affecting the system.

3. A ballasting system for a locomotive according to claim 1, wherein the connection between the piston rod of the second mentioned cylinder and the spring supporting member of the truck comprises a fixed guide projection on said member apertured for free passage of the piston rod downwardly through it, and a damping spring interposed between said projection and a collar on the protruding end of said piston rod permitting normal up and down movements of the truck without affecting the ballasting system.

4. A ballasting system for a locomotive having a body with a fuel-consuming power source in one end thereof, and a fuel compartment at the other end thereof, separately powered driving wheel trucks with spring suspensions yieldingly supporting the body respectively beneath the power source and beneath the compartment, a pilot truck associated with the powered truck beneath the fuel compartment, and a coupled tender; said system including a ballast water compartment in the fuel compartment end of the locomotive body, a water storage compartment

ment in the tender, piping extending between the ballast water compartment on the locomotive and the tender, a continually running pump interposed with a flow-control valve and with a spring influential upon the piston to maintain the valve normally set for idle circulation of water in the pump, a vertically-arranged cylinder mounted upon a spring cushioned member of the pilot truck with its piston connected to a spring supporting member of said pilot truck, and a flexible conduit serially connecting the two cylinders, whereby upon relaxation of the springs of the pilot truck as fuel is consumed, liquid is displaced from the last mentioned cylinder to move the piston from the first mentioned cylinder for actuation of the valve and transfer of fuel weight loss compensating water from the tender to the ballast water compartment and maintenance thereby of a constant load on the powered truck beneath the fuel compartment end of the locomotive body.

5. A ballasting system for a locomotive according to claim 4, wherein the connection between the piston rod of the second mentioned cylinder is flexible to the extent of permitting normal up and down movement of the pilot truck without affecting the ballast system.

6. A ballasting system for a locomotive according to claim 4, wherein the connection between the piston rod of the second mentioned cylinder and the spring-supporting member of the pilot truck comprises a fixed guide projection on said member apertured for passage of said piston rod downwardly through it, and a damping spring interposed between said projection and a collar on the protruding end of said piston rod permitting normal up and down movements of the pilot truck without affecting the ballasting system.
